Roger Kennedy, Attorney
ATTORNEYS

UNITED STATES PATENT OFFICE.

HENRY W. O'DOWD, OF JERSEY CITY, NEW JERSEY, ASSIGNOR TO STANDARD GAS EQUIPMENT CORPORATION, A CORPORATION OF MARYLAND.

GAS BROILER.

Application filed December 31, 1925. Serial No. 78,523.

The invention relates, more particularly, to gas broilers, toasters, and the like, in which the heat from the flame jets is directed downwardly upon the material to be treated.

5 A common form of gas broiler, is made with an oblong open-faced broiling chamber in which, along the opposite upper sides, extend Bunsen burner tubes having pipes branching laterally therefrom across the upper part of the broiling chamber. These branch pipes are formed with flame ports in their lower sides from which the flame jets extend downwardly toward the grid on which is placed the food to be broiled.

10 15 A gas broiler constructed in the manner of the art, as above described, has certain serious inherent defects. The branch pipes warp; deleterious matter, as oxide of iron flaked from the pipes, and moisture of condensation, falls upon the cooking food; and, moreover, secondary air to support combustion is not supplied in a proper manner or quantity. These and other defects will be apparent to those skilled in the art.

20 25 With the foregoing defects in view, the present invention provides a construction of gas broiler or other gas apparatus of similar operation, in which the burner tubes are located at the opposite upper sides of the broiling chamber outside the zone of the grid. Within said zone and directly over the grid is sustained a heat deflecting element which radiates and deflects downwardly the heat from the flame jets sent into said zone by the burner tubes, and there is associated with each burner tube and the heat deflecting element a burner plate formed with secondary air discharge openings adjacent the flame ports of the burner tube.

30 35 40 The foregoing construction is such, also, as to lend itself to other advantageous features which will be brought out in the following description of the construction and arrangement of the parts of a preferred embodiment of the invention.

45 Of the accompanying drawings:

Fig. 1 is a front view, partly in section, of the upper part of a gas range showing the open front broiling chamber with the heating members constructed in accordance with the invention, parts being broken away;

50 55 Fig. 2 is a top plan view of the same, parts being broken away;

Fig. 3 is a perspective view of a heat-deflecting member, burner tube, and burner

and baffle plates, parts being broken away, showing the relative disposition and arrangement thereof;

Fig. 4 is a side view of a burner tube, showing its laterally disposed flame ports, 60 and indicating by the dotted lines the method of removing the same from the range; and

Fig. 5 is a top plan view of a gas broiler, parts being broken away, illustrating a modification of the burner unit. 65

Referring in detail to the drawings, and first to Figs. 1 to 3, inclusive, there is illustrated therein a gas broiler or toaster, having its heating parts made in accordance 70 with the invention. The broiler is made in the conventional casing of oblong form, a frame 7 forming an open front. A partition 8 forms a rear wall for the broiling chamber 9 and extends parallel with the rear wall 75 10 of the casing from the bottom to the top of the casing and from side to side thereof, and encloses with said rear wall an insulating space 12, all as shown in Fig. 2.

Burner tubes 13, 14 are provided, and in 80 order to avoid the objections noted with respect to the burner tubes extending across the broiling chamber above the food, such as warping of the tubes, inaccessibility for cleaning, and the dropping of deleterious 85 matter upon the cooking food, said tubes are disposed outside the zone of the grid in the upper part of the broiling chamber along the opposite sides thereof, see Fig. 2. Said tubes have on their rear ends ears 16 adapted to rest on brackets 17 secured to said partition 8. At their front ends said tubes rest on the frame 7 and have depending portions 18 ending in the customary air chambers 19.

Gas is supplied from pipes 20, having cocks 95 21, and leading from a manifold 22. It will be seen, see Figs. 2 and 4, that this construction affords the advantage, according to one feature of the invention, that by slightly lifting the tubes at their outer ends they may be 100 readily withdrawn from the broiler for any purpose, as for cleaning or replacing. On their inner sides said tubes 13, 14 are formed with flame ports 23 laterally and inwardly directed. In operation, the flame jets from 105 the burner ports will be made to reach horizontally nearly to the vertical center of the broiling chamber 9.

The food to be cooked is placed upon a grid 24, which may be located in the broil- 110

ing chamber at a convenient level below the gas tubes 13, 14 by means of supporting side ledges 25. In order that the heat from the flame jets may be brought to bear upon the food, a heat-deflecting element is provided between said gas tubes, said elements preferably being composed of individual deflectors 26, 27 arranged in the broiling chamber with their body portions above the level of the flame ports and jets. To sustain each deflector in proper position a horizontal bracket 28 having a depending flange 29 is secured to the wall 8 by screws 31. At the front of the chamber 9 a flange 32 of the frame 7 projects inwardly. A supporting member 33 is laid on the bracket 28 and flange 32 centrally thereof and is secured to the bracket 28 by screws 34. This member 33 is cast with a central rib 36, dividing the upper part of the broiler into two flue compartments. Baffle plates 37, 38 are secured to the bracket 28 and flange 32 near their outer ends but inwardly of the burner tubes 13, 14, being fastened to the bracket 28 by screws 39. These baffle plates will be hereinafter further described. On the framework thus outlined are laid the deflector members 26, 27, their inner edges, which are spaced apart, forming with said rib 36 passages 41, 42 to which further allusion will presently be made. As shown in Figs. 1 and 2, said deflectors extend from the front frame 7 of the casing to the rear wall 8 of the broiling chamber and from the supporting member 33 nearly to the respective gas tubes 13, 14. It will be noted that said deflector members may be readily removed through the front of the casing, a lid 43, provided with handles 44, being slideable vertically in the upper part of the frame 7 in a conventional manner and thus permitting such removal, see Figs. 1 and 2.

The flame jets from the flame ports 23 will play horizontally under said deflectors throughout their entire extent and, in order to promote perfect combustion, ribs 46 depend from the under sides of the deflectors between the several flames, forming grooves 50 which register with the flame ports 23. These grooves in effect form separate combustion chambers for the respective flame jets. The heated products of combustion will pass out of said chambers into the passages 41, 42 and thence back to a chimney 47 rising from the rear center of the top of the casing. The rib 36, besides serving as a wall for said passages 41, 42, prevents any meeting and commingling of the heated products of combustion coming from opposite directions and any disturbances resulting therefrom which would interfere with proper combustion. It will be seen that in the construction thus formed adverse currents and eddies in the flow of the

heated products of combustion will be prevented, complete combustion thus promoted, and the heat from the flame jets will be deflected downwardly upon the food being broiled. Further to increase the heating efficiency of the broiler, the deflecting members 26, 27 are made of suitable incandescent material which will be heated to incandescence by contact with the flame jets, and in turn these incandescent deflectors 75 will radiate heat down upon the grid containing the food to be broiled. The ribs 46 in addition to their function in forming combustion chambers for the flame jets serve also to increase the reflecting and radiating 80 surfaces of the deflecting members. These surfaces are yet further increased by protuberances 48 which may be of any suitable size and shape but which do not depend low enough to interfere with the flame 85 jets.

It is desirable that the heat should be deflected and radiated down upon the grid containing the food being broiled evenly and equally throughout the length of the 90 flame jets. As, however, the heat efficiency of the flame jets is greater near the beginnings or stems thereof, said baffle plates 37, 38 are provided, extending from the flame ports a suitable distance under the ribs 95 46 and so serving to check the downward flow of the heat at the place of its greatest strength, and to send some of this heat forward. In order, however, that the heat may not thus be checked in too great a degree, said plates 37, 38 are formed with perforations 49 so proportioned that the proper amount of heat will be permitted to pass the baffle plates. It may be noted, also, that the closed top of the broiler will 100 absorb the heat from the outflowing heated products of combustion and will likewise receive some heat by radiation from the heat deflecting members, all in such degree as to be useful in keeping warm 110 any articles already heated and placed on said top.

It is to be observed that as the flame jets must be of great length, less than the ordinary amount of primary air should be mixed 115 with the gas. In order, therefore, to develop flame jets capable of giving off the required quantity of heat, secondary air must be supplied in volume properly proportioned to the low intake of primary air and at a proper time and in a proper manner. For this purpose, therefore, there is provided, between the flame ports 23 and the adjacent edges of the deflectors 26, 27 and extending from the baffle plates 37 to the top 120 of the casing and from the front of the broiling chamber to the rear wall 8 thereof, burner plates 51 which may be conveniently formed as vertical flanges of the baffle plates 37. These burner plates 51 are formed with 130

secondary air discharge openings 52 adjacent the flame ports 23 and of greater diameter. It will be seen that by reason of the construction thus described secondary air will be supplied to the flame jets at their stems from above as well as below. It is to be noted, also, that as the flame jets are spaced apart from the roofs of the grooves, in their passage therethrough they will be supplied from above with such further secondary air as they need.

A modification of the invention is shown in Fig. 5, the gas broiler in this instance being provided with a burner unit so constructed and arranged as to be capable of use as a whole or in either its front or rear parts separately. The casing of the broiler is similar to the casing heretofore described, but one heat-deflecting member 26^a is preferably provided instead of two as in the prior construction. To support the deflector a framework generally similar to that heretofore described is provided, the parts being similarly numbered, see Fig. 5, adding in each instance the exponent "a," the central supporting member 33 being omitted. Burner tubes 13^a, 14^a are located and removably mounted as in the other construction. These burners, however, are provided each with flame ports 23^a for half its length and in opposite halves, that is to say, one tube, say 13^a, is provided with flame ports in its forward half, while the other tube 14^a has them in its rearward half, as shown in said Fig. 5. It will be seen, therefore, that if only one burner tube is operated, only that part of the heat deflector 26^a will be heated to incandescence which is immediately opposite the flame ports being used. With the construction thus shown and described, however, the broiling may be done in either the forward or rear part of the broiling chamber, as may be desirable, with a consequent economy in operation. And if occasion require, the heat deflector 26^a may be utilized to its full capacity by using both burner tubes 13^a, 14^a. It should be noted that the flame jets in this construction will extend throughout substantially the entire length of the grooves or combustion chambers and the heated products of combustion will pass through them, being given an upward direction by the burner plate 51^a and curling over the top of the heat deflector to flow to the chimney (not shown in said Fig. 5) rising from the rear center of the casing top. It should be noted, also, that the burner plates 51^a in this case are formed without any secondary air discharge openings 52^a in those parts where the said heated products of combustion pass, whereby no diversion of said products from their proper path is permitted.

The invention in its broader aspects is not limited to the precise constructions shown

and described as many changes may be made in the details thereof without departing from the main principles of the invention or sacrificing its chief advantages.

Having thus described my invention, what I claim is:

1. In a gas broiler, the combination of a casing, a burner therein formed with laterally directed flame ports, a heat deflector sustained laterally adjacent said flame ports, and a baffle plate extending under the edge portion only of the deflector adjacent the flame ports, whereby the heat is deflected downwardly in uniform degree throughout the length of the flame jets. 75

2. A gas burner unit comprising a pair of tubes, each tube having inwardly directed flame ports in a part thereof and a blank part, and said tubes being arranged with the flame ports of one tube opposite the blank 85 part of the other tube.

3. A gas burner unit comprising a pair of oppositely disposed tubes having each inwardly directed flame ports in a part thereof and a blank part, one tube having said ports 90 in its forward part and the other tube having said ports in its rear part.

4. In a gas broiler, the combination of a casing, and two independent burners arranged therein, one having a blank part and 95 its flame ports restricted to the forward part of the casing, and the other having a blank part and its flame ports restricted to the rear part of the casing.

5. In a gas broiler, the combination of a burner formed with laterally directed flame ports, and a heat deflector composed of a slab of refractory material formed with grooves, the body of said slab being arranged above the level of said flame ports and said 105 grooves being aligned with the flame ports to constitute combustion chambers for the individual flame jets, and said deflector being arranged to radiate the heat downwardly directly upon the article to be heated. 110

6. In a gas broiler, the combination of a burner formed with laterally directed flame ports, and a heat deflector composed of a slab of refractory material sustained laterally adjacent and with its body portion arranged above the level of the flame ports and formed with depending ribs forming grooves aligned with the flame ports and which constitute combustion chambers for the individual flame jets, and said deflector 115 being arranged to radiate the heat downwardly directly upon the article to be heated. 120

7. In a gas broiler, the combination of a burner formed with laterally directed flame ports, and a heat deflector composed of a slab of refractory material sustained laterally adjacent and above the level of the flame ports and formed with grooves aligned with the flame ports to constitute combustion chambers for the individual flame jets, said 125 130

deflector being arranged to radiate the heat downwardly directly upon the article to be heated, and said grooves containing protuberances at different points in their length 5 to increase the heat radiating surfaces, without interfering with the flame jets.

8. In a gas broiler, the combination of a burner formed with laterally directed flame ports, and a heat deflector composed of a 10 slab of refractory material sustained laterally adjacent and with its body portion arranged above the level of the flame ports and formed with depending ribs forming grooves aligned with the flame ports and 15 which constitute combustion chambers for the individual flame jets, said deflector being arranged to radiate the heat downwardly directly upon the article to be heated, and means associated with said burner for regulating the supply of secondary air to the 20 upper sides of the flame jets.

9. In a gas broiler, the combination of a 25 casing, a burner tube extending fore-and-aft of the casing and formed with laterally directed flame ports, a heat deflector sustained laterally adjacent and with its body portion above the flame ports and arranged to deflect downwardly heat from the flame jets directly upon the article to be heated,

and a burner plate disposed between the 30 burner and heat deflector and formed with secondary air discharge openings therein adjacent the flame ports, thru which openings secondary air is supplied to the upper sides of the flame jets.

10. In a gas heating apparatus, the combination of a casing, a pair of burner tubes arranged in said casing at the opposite sides thereof, each tube having inwardly directed flame ports in a part thereof and a blank 40 part, said tubes being arranged with the flame ports of one tube opposite the blank part of the other tube, a heat deflector arranged horizontally between said tubes and with its body portion above the level of said 45 flame ports, a burner plate disposed between each burner tube and the adjacent edge of the heat deflector and formed with secondary air discharge openings therein opposite the flame ports, and a blank portion 50 opposite the blank portion of the adjacent burner, whereby heated products of combustion will pass the blank part of said plate without diversion from their proper path.

In testimony whereof, I have affixed my 55 signature hereto.

HENRY W. O'DOWD.
